UNITED STATES PATENT OFFICE.

ARTHUR C. VARNUM AND JAMES ERNEST BIRDSALL, OF SOUTHBRIDGE, MASSACHUSETTS.

THREAD-CLAMPING MECHANISM FOR LOOMS.

Application filed May 6, 1926. Serial No. 107,207.

This invention relates to a thread-clamping mechanism for looms and constitutes improvements over the device shown in our Patent No. 1,480,480, patented January 8, 5 1924. The principal object of this invention is to provide a self-aligning construction for a thread clamping device of the nature set forth in said patent so as to provide for the automatic adjustment of the 10 roller with respect to the thread or other surface against which it comes into contact; and also to provide for applying the invention to other types of thread clamping mechanism than the one shown in said patent. 15

Reference is to be had to the accompanying drawings in which

Fig. 1 is a transverse sectional view of a part of a loom showing one way in which 20 the present improvements can be applied thereto;

Fig. 2 is a view in side elevation on enlarged scale of the thread clamping mechanism by itself shown in open position;

Fig. 3 is a plan of the parts shown in 25 Fig. 2;

Fig. 4 is a view similar to Fig. 2 showing the opposite or cutting position of the parts;

Fig. 5 is an enlarged sectional view of 30 one form of the self-aligning roller;

Fig. 6 is a view similar to Fig. 1 showing the application of the invention to a different type of automatic filling replenishing 35 looms;

Fig. 7 is a view similar to Fig. 2 on enlarged scale of the form in Fig. 6;

Fig. 8 is a similar view showing the part 40 in a cutting position;

Fig. 9 is a bottom plan of the same; and

Fig. 10 is a sectional view showing one 45 form of self-aligning roller.

Referring first to Figs. 1 to 5, we have shown the invention as applied to a loom having the usual lay 11 carrying the shuttle box 12 oscillated in the usual manner. The magazine 13 is shown as co-operating with the weft replenishing mechanism operated by a rock shaft 14. The details of this 50 mechanism need not be described but a shuttle feeler member 15 is pivotally mounted at 16 and adapted to be maintained

normally in operative position with respect to the lay by means of a spring 17. This 55 spring acts through an arm 18 constituting a part of the feeler member 15. A lever 19 fixed on the rock shaft 14 is arranged to swing the feeler member 15 in the usual manner.

The upper end of the feeler 15 is provided with a V-shaped notch 20 to receive the filling thread when the feeler is moved into operative position with respect to the shuttle box. A fixed blade 21 is secured to the feeler 15 at the lower edge of the notch 65 and a pivoted cutting blade 22 is mounted to swing on a stud 23 mounted on the feeler member. The blade 22 is provided with a heel portion 24 adapted to be engaged by the lay in the usual manner. This swings 70 the blade 22 to part the thread between the co-operating edges of the blades 21 and 22. The blade can be opened by means of its pin 75 25 as is well understood in this art. These parts of the loom are old and well known and described in our above mentioned patent.

A plate 28 is held stationary by a fork 26 and pin 27, the heel portion 24 having a hole 27^a for receiving the pin 27 and allowing 80 the blade 22 to swing. The opposite edges of the hole constitute limiting stops.

The heel portion 24 has an offset 31 and having in said offset a roller 32. This roller 85 as shown in Fig. 5, is of a hollow cylindrical form mounted on a convex shaft 33 which is held at its ends in two openings in the offset 31. It can be put in from one end and when the roller is on it the roller will be free to swing slightly on account of irregularities in the position of the thread or other parts. This roller co-operates with the stationary plate 28 fixed on the stud 23 and held in stationary position by the pin 27. A spring 29 under the head of the stud 23 holds this plate and all the parts yieldingly together. 90

In operation, the parts being open as shown in Fig. 2, the thread is passed through the notch 20 and over a horizontal projection on the end of the plate 28. The movement of the pin 25 upwardly by the mechanism of the loom as described in said patent 100 results in swinging the blade 22, cutting the

thread between the blades 21 and 22 and holding its end between the roller 32 and the outer end of the stationary plate 28.

In the form shown in Figs. 6 to 10 there are parts corresponding to the parts above described and it will be understood that this is the application of this invention to a different type of loom. In this case, the shuttle 10 feeler member 35 operates in a well known way and has a notch 40 similar to the notch 20. It also has a stationary blade 41 spaced from the notch 40 and a stationary plate 36 provided with an offset and roller 32 like the roller above described but mounted on a bar-shaped support 51 so as to be capable of yielding as in the other case. Between the fixed blade 41 and the roller is a swinging blade 42 cooperating with both. A spring 39 holds the parts in contact. Here the 20 thread is cut between the stationary blade 41 and swinging blade 42 as in the other case and the thread is held between the roller 32 and the other side of the oscillating blade 42 as above described.

25 This provides an automatic filling replenishing loom with means for clamping the thread comprising a self-aligning roller on a pin or bushing so that the roller surface will adjust itself to the blade, plate or other 30 flat surface with which it comes in contact.

Although we have illustrated and described only two forms of the invention we are aware of the fact that other modifications can be made therein by any person skilled in the art to adapt it to other looms 35 without departing from the scope of the invention as expressed in the claims.

Therefore, we do not wish to be limited to all the details of construction herein shown and described, but what we do claim is:

1. In an automatic filling replenishing loom, the combination with a thread parter 40 adapted to act upon the thread of the filling supply to be abandoned, and comprising a pair of blades adapted to have a relative movement, and a surface of revolution movable with one of them as a whole and mounted to tilt on its axis to accommodate itself to any irregularities.

2. In an automatic filling replenishing 50 loom, the combination with a thread parter, of a pair of blades for cutting the thread and two relatively movable members for holding the end of the cut thread, spaced from the blades and comprising a surface of revolution 55 for holding the thread between it and the other member for holding the end, said surface of revolution being mounted to tilt freely, for the purpose described.

3. In an automatic filling replenishing 60 loom, the combination with a thread parter, a blade fixed with respect thereto and spaced therefrom, a tilting member having a blade 65 cooperating with the first named blades to cut the thread, and a roller on a fixed axis for engaging with the spaced blade to hold the cut end of the thread, said roller being capable of tilting on a longitudinal axis to accommodate irregularities in the thread.

In testimony whereof we have hereunto 70 affixed our signatures.

ARTHUR C. VARNUM.
JAMES ERNEST BIRDSALL.
